UNITED STATES PATENT OFFICE.

OTIS E. DROWN, OF LINCOLN, RHODE ISLAND.

MACHINE FOR DRYING WADDING.

SPECIFICATION forming part of Letters Patent No. 554,585, dated February 11, 1896.

Application filed July 5, 1894. Serial No. 516,594. (No model.)

To all whom it may concern:

Be it known that I, OTIS E. DROWN, a citizen of the United States, residing in the town of Lincoln, in the county of Providence and 5 State of Rhode Island, have invented certain new and useful Improvements in Manufacture of and Mechanism for Making and Drying Wadding, &c.; and I do hereby declare the following to be a full, clear, and exact description of the invention, such as will enable others skilled in the art to which it appertains to make and use the same, reference being had to the accompanying drawings, and 10 to letters of reference marked thereon, which 15 form a part of this specification.

My invention relates to improvements in the manufacture of and mechanism for making wadding—that is, the production of a continuous web of loosely-carded material, as 20 cotton—the same being continuously sized or starched on both sides and dried while connected with the web issuing from the card and subsequently book-folded or cut into sheets, as desired.

25 In drying apparatus hitherto employed the devices have usually been so constructed and arranged that the heated air was permitted to escape before it had been sufficiently charged with moisture, thereby materially increasing 30 the operating expenses. Such former devices not only required a greater amount of fuel to supply the needed heat or steam, but the corresponding output was greatly reduced, as compared with the improvements forming the 35 subject of my present invention.

My invention consists, essentially, in producing a continuous web of fibrous material, as cotton, sizing or starching both sides of the traveling web, passing it through a heated 40 drying-chamber to evaporate the moisture from the thus-treated web, exhausting the moisture-laden hot air from the chamber, admitting outer or cold air to the heating-chamber to replace the exhausted hot air, and 45 finally converting the thus-produced web of wadding into sheets, layers or rollers, as desired.

It further consists in providing the upper portion of the heating-room or drying-chamber 50 with a series of diaphragms or partitions arranged above one another to form inter-communicating smaller chambers communi-

cating with the lower portion of the main chamber, all as will be more fully hereinafter set forth and claimed.

In the accompanying two sheets of drawings, illustrating my invention, Figure 1, Sheet 1, is a vertical longitudinal sectional view, in partial elevation, on line *o o* of Fig. 2. Fig. 2 is a transverse sectional view taken 60 on line *x x* of Fig. 1. Fig. 3 is a similar sectional view of a heating-chamber, &c., as usually constructed; and Fig. 4 shows a modified form of the diaphragm.

I would state here that I do not broadly 65 claim mechanisms for producing a continuous web of cotton wadding. The novelty of my invention resides, essentially, in the construction of the drying room or chamber, and through which latter the web is carried back 70 and forth. Means for producing the web, as a card A, suitably-actuated sizing or starching rolls, as B, between which the web is passed continuously, thereby sizing both sides of the web, and a series of suitably-supported 75 continuously-traveling endless aprons or conveyors, as C, for carrying the web back and forth through the drying room or chamber, as D, are all old. Fig. 3 shows an arrangement of such well-known devices. In said 80 figure the drying-chamber D is simply a comparatively-large room having a heating-coil E or other suitable heating means located in the lower portion thereof and having in the upper portion the series of endless-web conveyors C arranged above one another. When thus constructed or arranged, it will be seen

that most of the heated air in rising simply comes in contact with the under side of the lower apron and its load and then flows or 90 passes upwardly to the right and left past the edges of the other aprons and finally escapes through the exhaust-passage *m*. (See arrow-direction, &c., Fig. 3.) Obviously in the arrangement last referred to the heated air will 95 or at least is liable to pass out of the chamber before it takes up or absorbs a sufficient amount of moisture. Consequently the operation must be longer continued, thus increasing the cost in order to thoroughly free 100 the web of all its moisture.

In my improved drying room or chamber H the heating means or coils E are or may be substantially the same as indicated in said

Fig. 3, since I make no claim herewith to such part of the apparatus. The same also applies with respect to the carding-engine A, sizing-rolls B, and the series of endless aprons or 5 conveyers C, arranged to receive the continuous web from the card and carry it back and forth through and longitudinally of the drying-chamber.

At or near the bottom of the drying-room 10 II, I prefer to locate a series of controllable intake or cold-air ducts b. These furnish cold air to the chamber to supply or take the place of the discharged heated air, the latter being exhausted mechanically or in any other suitable manner into a passage d communicating with the top of the chamber.

The series of endless carriers or conveyers C are located in the upper portion of the drying-room II and about midway of the same 20 transversely. (See Fig. 2.) They extend longitudinally of the drying-room and, as drawn, pass through narrow openings h, formed in the end walls h². (See Fig. 1.) In order to provide ample time, &c., for the passage of the 25 continuous web w back and forth through the room II, I may make the latter some sixty feet to seventy-five feet long. Each carrier or apron C may consist of a pair of linked chains united laterally at intervals and adapted to 30 support the web w, as common, the chains in turn being supported or guided by side brackets a secured to uprights f.

Just above each carrier C is secured a diaphragm or partition P. These extend substantially the length of the drying-room, but do not extend entirely across it transversely. As drawn, (see Fig. 2,) I have shown two of 35 such partitions, the same being arranged in a zigzag manner—that is, one edge forms a close 40 joint with the side wall of the room and the other or free edge falls short of the adjacent wall—thereby forming a space or opening s for the passage of the heated air. The other partition is reversely arranged with respect 45 to the first-named or lower partition. Consequently the heated air as it passes upwardly from the lower portion of the drying-room into the exhaust-passage d is compelled to travel in a circuitous or zigzag course. In 50 order to further increase the efficiency of the device, I prefer to make the surface of the partitions P bright or planished. Continuous sheets of copper or tin answer very well for the purpose. I prefer also to set the partitions at a slight angle with respect to the 55 horizontally-traveling web of material w, as shown in Fig. 2.

By means of the construction and arrangement just described it is apparent that the 60 heated air in rising will first come in contact with the under side of the traveling web, resting on the bottom carrier, and with the under side of the lower partition, the latter at the same time radiating heat from its surface onto 65 the upper side of the web adjacent thereto. The heat then passes around the end or side edge of said partition through opening s and

comes in contact with the other partition and the corresponding portion of the web. Thence the heat passes around the free edge of the 70 last-named partition into the top space, in which is located the last carrier, and into the exhaust-passage d. A blower or other mechanically-actuated analogous device may be connected with the opening d, whereby the 75 moisture-laden heated air may be exhausted from the drying-room and thus produce circulation, cold air at the same time being supplied into the room II through the ducts or 80 passages b.

I would state that although I have shown two partitions, P, it is obvious that any other number of them may be employed, the carriers being arranged correspondingly. The partitions may be made readily removable if 85 desired. They may also be provided with dampers or gates, as g, Fig. 4, for controlling the openings s without departing from the spirit of the invention.

I claim as my invention—

1. In a drying apparatus for wadding or other continuous material, the combination with a heating-chamber and carriers therein for the wadding extending lengthwise of the chamber, of diaphragms arranged one above 95 the other, extending transversely of the chamber each closing the ascent of the heated air at one side of the chamber and leaving an opening or passage therefor on the other side, said closures and openings being arranged on 100 opposite sides alternately whereby there is formed a zigzag passage for the heated air transverse to the path of the wadding, substantially as described.

2. In a drying apparatus, for wadding or 105 other continuous material, the combination, with a heating-chamber, of endless aprons adapted to convey the wadding through said chamber, and rollers for said aprons and independent rollers for turning said wadding, 110 substantially as described.

3. In a drying apparatus for wadding or other continuous material, the combination, with a heating-chamber, of endless aprons to 115 carry the wadding through said chamber, rollers for the aprons located outside said chamber, the latter being provided with openings for said aprons, diaphragms arranged one 120 above another, extending transversely of the chamber each closing the ascent of the heated air at one side of the chamber and leaving an opening or passage therefor on the other side, said closures and openings being arranged on 125 opposite sides alternately whereby there is formed a zigzag passage for the heated air transverse to the path of the wadding, substantially as described.

In testimony whereof I have affixed my signature in presence of two witnesses.

OTIS E. DROWN.
